C. H. ALLAN

PLURAL TONGUE TYPAN GAUGE

Filed May 1, 1928

By *Leuchtmann, Bryant & Dailey*
Attorneys

UNITED STATES PATENT OFFICE.

CHARLES H. ALLAN, OF RYEGATE, MONTANA.

PLURAL-TONGUE TYMPAN GAUGE.

Application filed May 1, 1928. Serial No. 274,277.

The present invention relates to improvements in tympan gauges and has particular reference to the provision of such a gauge with a number of superposed guide tongues.

5 Ordinarily, gauges of this type are provided with a single guide tongue which is adapted to accommodate, well enough, stock up to a certain thickness, but by the provision of a plurality of superposed tongues, 10 as contemplated by the present invention, stock of any thickness may be accommodated merely by adjusting the proper tongue to operative position. Preferably two tongues are provided, since this number will ordinarily be sufficient. In the following 15 description, I have set forth the invention as applied to a gauge having a prong adapted to engage the tympan sheet for retaining the gauge in position, and while I shall describe and claim certain novel features in the manner of mounting the tongues in such a gauge, it is to be understood that my broad invention is adapted to be applied to tympan gauges of all descriptions.

25 Referring to the drawings,

Figure 1 is a perspective view of a gauge embodying the present invention.

Figure 2 is a side elevation of the gauge.

Figure 3 is a top plan view of the gauge, 30 and

Figure 4 is a bottom plan view of the same.

Referring now to the drawings, 10 indicates a gauge body or frame composed of a strip of suitable spring metal bent in substantially the shape of a rectangle. The lower side 11 of this rectangle is slotted as at 12 and 13, Figures 1 and 4, to form a prong 14 adapted to be engaged in a tympan sheet in the well-known manner. The marginal portions of the lower side have scroll ends as at 15 and 16, so as to enable them to slide freely over the tympan sheet in engaging the prong.

45 The top side 11' of the frame 10 has fingers 17 and 18 punched inwardly thereof, these fingers being substantially T-shaped as shown, aligned, and extending in opposite directions, the head portions being apertured 50 to receive freely therethrough the upper tongue 19. Tongue 19 is guided in slots formed in the end walls 20 and 21 of the gauge body adjacent the tops thereof, and somewhat below these slots the walls are 55 provided with similar slots adapted to receive and guide tongue 22, these tongues

being substantially parallel, and in the vertical planes of the fingers. As may be most clearly seen from Figure 2, finger 17 is bent downwardly and then upwardly so that its free end engages the under surface of tongue 19, while finger 18 is bent downwardly so that its free end engages the top surface of tongue 22. The ends of the fingers bear against the tongues with sufficient pressure to retain the latter, by frictional contact, in their adjusted positions.

It will be obvious that the gauge has been illustrated in an exaggerated size, and that in actual practice it will approximate the size of similar gauges as now on the market. When thin stock is to be printed, tongue 22 will be adjusted to operative position, but when stock of greater thickness than can be conveniently taken care of by tongue 22 is to be printed, the latter is withdrawn and tongue 19 advanced to operative position. By reason of this alternateness of adjustment, the device, as shown, will be found to be a great convenience in shops where stock of considerable variation in thickness has to be printed.

As I have explained above, however, the embodiment shown and described is intended to be illustrated, rather than restrictive of my invention, the scope of which is determined in the following claims.

I claim:

1. A gauge comprising a body element adapted to be operatively positioned on a tympan, and a plurality of guide tongues spaced vertically of the body element, said tongues being adapted to be alternatively disposed in operative position relative to the body element to accommodate stock of different thicknesses.

2. A gauge comprising a body element adapted to be operatively positioned on a tympan, and a plurality of substantially parallel superposed guide tongues slidably mounted in the body element, said tongues being adapted to be alternatively disposed in operative position relative to the body element to accommodate stock of different thicknesses.

3. A gauge comprising a body element adapted to be operatively positioned on a tympan, a plurality of substantially parallel superposed guide tongues slidably mounted in the body element, and spring pressed means engaging said tongues to yieldingly restrain movements thereof, said tongues

being adapted to be alternatively disposed in operative position relative to the body element to accommodate stock of different thicknesses.

5. 4. A gauge comprising a body element adapted to be operatively positioned on a tympan, a plurality of substantially parallel superposed guide tongues slidably mounted in the body element, and yieldable means 10 pressing laterally in opposite directions against the tongues, said tongues being adapted to be alternatively disposed in operative position relative to the body element to accommodate stock of different thick- 15 nesses.

5. A gauge comprising a body element adapted to be operatively positioned on a tympan, a plurality of substantially parallel superposed guide tongues slidably mounted 20 in the body element, and yieldable means interposed between the tongues and pressing them in opposite directions, said tongues being adapted to be alternatively disposed in operative position relative to the body element 25 to accommodate stock of different thicknesses.

6. A gauge comprising a sheet metal frame element adapted to be operatively positioned on a tympan, a plurality of substantially parallel superposed guide tongues 30 slidably mounted in the body element, and fingers struck from the metal of the frame and pressing laterally against said fingers to yieldingly restrain movement thereof, said 35 tongues being adapted to be alternatively disposed in operative position relative to the body element to accommodate stock of different thicknesses.

7. A gauge comprising a sheet metal frame element adapted to be operatively positioned on a tympan, a plurality of substantially parallel superposed guide tongues 40 slidably mounted in the body element, and fingers struck from the metal of the frame 45 and pressing laterally against said fingers in opposite directions to yielding restrain movement thereof, said tongues being adapted to be alternatively disposed in operative position relative to the body element 50 to accommodate stock of different thicknesses.

8. A gauge comprising a sheet metal frame element adapted to be operatively positioned on a tympan, a plurality of substantially parallel superposed guide tongues 55 slidably mounted in the body element, and fingers struck from the metal of the frame, the free ends of said fingers being disposed intermediate the tongues and pressing lat- 60 erally against the tongues in opposite directions to yieldingly restrain movement there-

of, said tongues being adapted to be alternatively disposed in operative position relative to the body element to accommodate stock of different thicknesses. 65

9. A gauge comprising a sheet metal frame having substantially horizontal top and bottom walls and vertical end walls, a plurality of fingers struck from one of the horizontal walls, and a plurality of substantially parallel superposed guide tongues slidably mounted in the end walls of said frame, each of said tongues being yieldingly engaged by the free end of one of said fingers. 70

10. A gauge comprising a sheet metal frame having substantially horizontal top and bottom walls and vertical end walls, a plurality of substantially aligned fingers struck from one of the horizontal walls, and a plurality of substantially parallel superposed guide tongues slidably mounted in the end walls of said frame in substantially the vertical plane of said fingers, each of said tongues being yieldably engaged by the free end of one of said fingers. 75

11. A gauge comprising a sheet metal frame having substantially horizontal top and bottom walls and vertical end walls, a plurality of substantially aligned oppositely extending fingers struck from one of said horizontal walls, and a plurality of substantially parallel superposed guide tongues slidably mounted in the end walls of said frame in substantially the vertical plane of said fingers, said fingers being apertured 90 near their attached ends to permit the passage therethrough of the tongue adjacent the finger-supporting wall, the free ends of said fingers being disposed intermediate the tongues and each bearing yieldably against one 95 of the fingers. 100

12. A gauge comprising a sheet metal frame having substantially horizontal top and bottom walls and vertical end walls, a plurality of substantially aligned oppositely extending fingers struck from the top wall, and a plurality of substantially parallel superposed guide tongues slidably mounted in the end walls of said frame in substantially the vertical plane of said fingers, said fingers being apertured near their attached ends to permit the passage therethrough of the tongue adjacent the top wall, the free ends of said fingers being disposed intermediate the tongues and bearing in opposite directions against the latter, the bottom wall of said frame being slotted to form a tympan-engaging prong. 105

In testimony whereof I have hereunto set my hand.

CHARLES H. ALLAN.
